UNITED STATES PATENT OFFICE.

EDWARD H. GRIM, OF DOTT, WEST VIRGINIA.

APPARATUS FOR OPERATING MINE DOORS, SWITCHES, OR THE LIKE.

Application filed June 20, 1923. Serial No. 646,731.

To all whom it may concern:

Be it known that I, EDWARD H. GRIM, a citizen of the United States, residing at Dott, in the county of Mercer and State of West Virginia, have invented certain new and useful Improvements in Apparatus for Operating Mine Doors, Switches, or the like, of which the following is a specification.

The invention resides in the provision of apparatus for controlling and indicating the movement of safety doors and switches such as are employed in mining operations and for movable elements of similar nature.

Primarily the invention has for its object to provide an apparatus of the class described which is of simple and relatively inexpensive construction and in which the parts are so constructed and correlative arranged as to effect the desired movement of the mine doors or switches in a safe and positive manner and whereby the operation of the said moving elements may be effected from a distance.

In its more detailed nature the invention has for its object the provision of electrically controlled means for operating mine doors and switches to permit the passing therethrough or thereover of the ore conveying cars, means mounted on the traveling cars whereby the operating means may be caused to function at the will of the operator riding on the cars and at any desired distance from the particular doors or switch, and means mounted on the traveling car and in view of the operator thereof for indicating the position of the distant doors or switch to be operated.

The invention further has for its object to provide electrically controlled and operated apparatus of the type stated in which the operating parts are driven by an electric motor, in which provision is made for preventing overloading of the motor during its operative function, in which the parts are so arranged as to permit a period of free operation of the motor before strain of actual operation is imposed thereupon, and wherein the parts are so designed and arranged as to effect a positive locking of the elements to be moved to their various positions.

With the above and other objects in view the invention resides in those novel details

of construction, combination and arrangement of parts, all of which will be fully described and then be specifically pointed out in the appended claims, reference being had to the accompanying drawings, in which:

Figure 1 is a partly diagrammatic perspective view illustrating my invention in operation.

Figure 2 is a cross section of the mine passage way illustrated in Figure 1, looking in the direction of the safety doors.

Figure 3 is a cross section taken substantially on the line 3-3 on Figure 2.

Figure 4 is a diagrammatic plan view illustrating the wiring system.

Figure 5 is a plan view of the control switch.

Figure 6 is a detail horizontal section illustrating the double shaft gear connection.

Figure 7 is a detail perspective view of one of the pendent door brackets.

Figure 8 is a detail horizontal section illustrating a modified form of operating screw shaft.

Figure 9 is a diagrammatic front elevation illustrating a modified form of door operating means.

Figure 10 is a detail cross section illustrating the motor connection for the form of the invention shown in Figure 9.

Figure 11 is a somewhat diagrammatic plan view of my invention operatively applied to a mine switch.

Figure 12 is a cross section taken across the switch at the interval of the operating screw.

In the drawings my invention is illustrated as operatively applied within a mine passage and as especially adaptable for operating safety doors or for controlling switches therein. While the invention has been practically illustrated in the connection just stated it should be readily understood that the invention is not limited to this use but is applicable to cooperation with any moving element such as comes within the scope of the appended claims.

In the adaptation of the invention as illustrated in the drawings, 1 indicates a track-way over which the mine cars carrying the mined coal or ore are drawn through the medium of the usual electric locomotive 2.

It is common practice in mining at the present day to provide the mine passages at intervals with safety doors and in the drawings, see Figure 1, I have illustrated a mine 5 passage as equipped with a safety wall 3, which may be supported in its proper relation with the mine walls by suitable timbers 4 such as are commonly used in this art. The cross wall 4 is provided with a suitable passage 10 or opening 5 through which the mine cars may pass, and this opening 5 is adapted to be closed normally, that is, while cars are not being drawn therethrough, by a pair of sliding doors 6 adapted to be guided, through the medium of door hangers 7 with which the doors are equipped, over a suitable guide rail 8 secured to the cross wall 3, and are adapted to meet and abut at the median line of the trackway 1.

20 The doors are equipped at their bottom edges with oppositely disposed pendent brackets 9, each of which includes a horizontally turned and elongated portion 10 provided with an elongated slot 11 disposed 25 in the direction of the length of the doors, see Figures 2 and 7.

A door operating nut 12 is slidably mounted in each slotway 11, and the said operating nuts each including an internally threaded bore, each adapted to receive one of a pair of cooperatively mounted operating screws 13 to which rotary motion is imparted from the motor 14. The screws 13 are disposed in horizontal relation, one with the other, 30 closely adjacent, and are joined to turn in opposite directions by small pinion gears 15 within the casing 16, which is mounted centrally of the cross wall 3, see Figures 1 and 2.

By reason of thus joining the operating 40 screws 13 by the pinions 15 the said screws may be made of the same pitch and when rotary motion is imparted to the same by the motor 14 the doors will be caused to move simultaneously, toward or from each other 45 as the case may be, to open or close the passageway through the cross wall 3 to permit passage of the coal or ore laden cars through the said cross wall, or to close the safety doors immediately after the passage of the cars therethrough.

A friction slip clutch 17 is spliced between the motor shaft and the operating screws adjacent thereto so that should the motor remain energized after the doors have reached 55 either limit of their movement the transmission connections will be allowed to slip to prevent overloading and destruction of the motor.

By reason of the slot connection between 60 the operating screws 13, the operating nuts 12 and the door brackets 9, a certain degree of free movement of the motor is permitted before actual working strain, due to the actual door opening or closing switch. By 65 permitting this degree of free movement of

the motor the same is allowed to speed up slightly before strain is placed thereupon and the life of the motor is extended by reason of thus relieving the motor of extreme strain incident to the sudden shock of operation which would otherwise be placed thereupon.

The mine wall may be suitably cut-away and tunneled and the timber 4 constructed to straddle the cut-away portion to make 70 suitable provisions for the positioning of the motor 14, see 18 on Figures 2 and 3.

In Figures 9 and 10 is illustrated a slight modification of the door opening and closing mechanism. In these figures the motor is 80 positioned with the driving shaft thereof in close alignment with the cross wall 3, and the said shaft is provided with a small driving pinion 19 adapted to mesh with a reduction gear 20, mounted on the door operating 85 cross shaft 21, mounted in any suitable way at proper position adjacent the bottom end of the cross wall 3, as illustrated in the figures referred to. The said operating shaft 21 is provided with a slip clutch connection 22 and a small pulley 23 adapted to cooperate with a similar pulley 23 mounted upon a cross shaft 24 disposed at the opposite bottom end of the cross wall 3. An endless operating rope is adapted to cooperate with 95 the pulleys 23 in effecting the opening and closing of the doors 6 and this endless rope 25 is wrapped once or more around each pulley 23 so that, when the motor is energized and rotary motion imparted thereby 100 to the shaft 21, the endless rope 25 will be caused to take the course indicated by the arrows on Figure 9.

A bracket 26 is pendent from each door 6 and the said brackets are so arranged that 105 one thereof cooperates with the upper travelling portion of the rope 25 and the other thereof cooperates with the lower travelling rope 25, see Figure 9. The rope 25 may be provided with abutments 27, a pair of which 110 cooperate with each pendent bracket 26.

When the motor is imparting rotary motion to the shaft 21 and thereby causing the rope to take the course indicated in Figure 9, the respective abutments 27 will engage 115 the pendent brackets 26 to effect the opening or closing, simultaneously, of the doors 6. It will be observed from Figure 9 that the abutments 27 are spaced some distance apart so as to allow a degree of free movement of the rope 25 before the actual opening or closing action is effected thereby, thus allowing a degree of free rotation of the motor for the purpose hereinbefore described.

In Figure 8 is illustrated a modified form 125 of the operating screws. In this form of the invention a single operating screw 28 is employed, the same being provided with a double pitch so that rotation thereof in 130

either direction will effect a simultaneous opening or closing of the doors as desired.

The usual trolley wire 30 is centrally disposed within the mine passageway so as to be in a central position when the doors are closed, as is clearly indicated in Figure 1. From this trolley wire 30 is obtained electrical energy for operating the locomotive which pulls the train of coal or ore laden 10 cars, also the energy for operating the motor 14 and for energizing the circuit for lighting the indicator signal in the manner presently to be described.

It is a purpose of this invention to make it possible for the operator of the mine locomotive to operate the doors from a distance and also to provide an indicating means whereby it is possible for him to know whether or not the doors have been properly 20 opened before he has approached the same too closely.

In carrying out these objects of the invention I provide a plurality, four being shown, of electrically energizable conducting 25 wires, 31, 32, 33 and 34, which are disposed at the side of and adjacent to the trackway 1 where they are suitably supported in the position shown in Figure 1 by suitable supporting brackets 35.

A contact making arm 36 is pivoted to the locomotive 2 in position for being raised into engagement with the wires 31, 32, 33 and 34, and the said arm is in the nature of a bell crank lever and is link connected, as at 38, 30 to an operating lever 39 whereby the operator of the locomotive may conveniently 45 lift the said arm into engagement with the said wires and a quadrant 40 is provided to cooperate with the lever to hold the same in the adjusted position so that the lever will slide along the wires and make electrical contact therewith in the manner soon to be described. As before referred to an indicator light 41 is provided at a suitable position within the range of vision of the operator of the locomotive and means is provided for lighting this light to indicate the position of the door before the locomotive has approached the same.

A control switch lever 42 is also mounted on the locomotive closely adjacent the lever 39 so as to be in convenient position for being operated by the driver of the locomotive for energizing the various circuits soon to be described.

By referring now more particularly to Figures 1 and 4 it will be observed that the numeral 43 represents, in diagram, the motor field, 44 the armature winding, 45 the wire connecting one end of the field 43 with the trolley wire 30. The wire 46 connects the other end of the motor field with the wire 32 which parallels the trackway 1. The two terminals of the armature winding are joined, one by the wire

47 to the wire 31 which parallels the trackway, and the other by the wire 48 with the wire 33 which parallels the trackway.

Suitably mounted upon a post or other supporting medium, such as is indicated in Figure 1, I provide a normally open circuit maker 49 of the common two-part type and the said circuit maker is in alignment with the line of travel of the adjacent door 6 and so positioned that when the door is forced open to the limit of its movement the same will engage the circuit maker to close the same. A wire 50 joins one terminal of the circuit maker 49 to a ground connection with the track rail, and the wire 51 joins the other terminal of the circuit maker to the wire 34 which parallels the trackway 1. By reason of the engagement of the circuit maker 49 by the door, at the limit of its opening movement, lighting of the signal 40 on the locomotive 2 is effected through electrical connections and in the manner later to be described.

The control switch lever 42 hereinbefore referred to cooperates with the control switch body 52 which is pivoted to the locomotive, as at 53, in position for being conveniently manipulated by the operator of the locomotive for controlling the operation of the door opening motor.

The switch body 52 includes a pair of cross contacts 54 so positioned as to leave a space therebetween on the under surface of the switch body 52 and being upturned around the sides of the switch body as in indicated at 55.

A pair of side contacts 56 are secured to the locomotive body in a manner for effecting ground connection therewith and in position for being engaged by the upturned portions 55 of the contacts 54 of the switch body as the same is moved to either side in the manner and for the purposes soon to be explained. It will be understood of course that the switch body 52 is constructed of suitable non-conductive material and properly insulated from the locomotive body.

A set of three contacts 57 cooperates with the switch contacts 54 and the same are disposed one at each side and in constant contact with the respective one of the movable contacts 54, and one disposed centrally thereof and projected into the blank space between the contacts 54, when the switch is in the normal position, so as only to be engaged when the switch body is moved to one side or another, see Figure 5.

It should be understood that the contacts 54 are also suitably insulated from the locomotive body.

Assuming the parts to be in the position illustrated in Figure 5, should the switch be moved toward the uppermost contact stop 56 as shown, it will readily be under-

stood that the cross contact 54 at that side will make connection between the said stop contact 56 and the contact 57 nearest adjacent thereto, and the opposite cross contact 54 will bridge and make contact between the remaining two contacts 57.

The contact making arm 36 is provided with contacting plates 58 so positioned that when the arm is lifted to the position indicated by the dotted line on Figure 1, the said contact plates will engage, in sliding relation, with the set of fixed contact wires 31, 32, 33 and 34 which parallels the trackway 1.

15 A wire 59 connects the plate 58 adapted to engage the wire 31 with one of the contacts 57. A wire 60 connects with the plate 58 adapted to engage with the wire 32 with the centrally disposed contact 57. A wire 20 61 connects with the contact plate 58 adapted to engage the wire 33 with the other contact plate 57. A wire 62 connects the contact plate 58 adapted to engage with the wire 34 with the indicating light or signal 25 41. The other terminal of the signal light 41 is connected by the wire 63 with the wire 60 which leads to the centrally disposed contact 57.

Assuming the parts to be positioned as 30 indicated in Figure 1, that is, with the doors locked to their closed position, by reason of the relation of the screws 13 with the operating nuts of the respective doors, and the switch lever 42 at its normal position and the contact making arm 36 at its normal 35 non-contacting position, the motor 14 would be de-energized and all mechanism out of operation.

40 While in the figure referred to, the locomotive is illustrated at a position fairly close to the doors to be opened it is to be understood that the mechanism of the invention is adapted to be operated from any distance from these doors for the purpose 45 of greater safety and for that purpose the indicating light 41 is provided to indicate clearly to the operator the position of the doors even before they have come into the range of his view.

50 By pulling down on the arm 39 the operator raises the arm 36 into sliding contact with the wires 31, 32, 33 and 34 paralleling the trackway. Upon making this contact by the arm 36 with the said wires it is immediately possible for the operator to ascertain the position in which the doors are at that time. Should the doors be at the open 55 position the light 41 would be lighted by reason of the completed circuit at 49 through the grounded wire 50, the wire 51, the wire 34, the wire 62, through the light, through the wire 63, through the wire 60, through the wire 32, through the wire 46, through the motor field 43 and through the wire 45 60 to the trolley 30.

Should the action of lifting the contact making arm reveal the fact that the safety doors were closed, as they should be, the operator would then proceed to set his switch to open the doors through the action of the motor and power transmission mechanism hereinbefore described in detail. The direction in which the switch would be thrown depends of course upon the winding of the armature and the pitch 75 of the operating screws 13. By throwing the switch into contact with the upper stop contact 56, indicated in Figure 5, it will be seen that a circuit will be completed by energizing the motor to cause rotation of the same in a particular direction as follows. Through the ground connection 56, the cross contact plate 54, the uppermost contact blade 57, the wires 59, 31, 47, 48, 33, 61, the remaining two contacts 57 and wires 60, 32, 46, through the motor field 43 and through the wire 45 to the trolley wire 30.

When the switch body 42 is shifted to the opposite position to that just above referred to, for the purpose of reversing the action of the motor, the circuit will be completed as follows. Through the lowermost grounded stop contact 56, the cross contact 54, the lowermost contact 57, the wires 61, 33, 48, 47, 31, 59, the remaining two contact blades 57, the wires 60, 32, 46, through the motor field 43 and through the wire 45 to the trolley wire 30.

100 In Figures 11 and 12 the invention is illustrated as applied in connection with a mine switch. In this illustration 64 indicates the straight trackway, 65 the curved trackway cooperative therewith and 66 the switch or movable element adapted to be shifted from one position to the other by action of the motor with the application of the peculiar mechanism of my invention.

105 The motor is indicated at 67 and the drive shaft 68 thereof is joined by a friction slip clutch connection 69 with the operating shaft portion 70 which is properly threaded at the desired pitch.

110 The individual parts of the movable switch element 66 are joined by the cross plate 71 which is provided with a longitudinal slotway 72 for providing a lost motion connection for the operating nut 73 provided with an internally threaded bore for accommodating the threaded portion of the operating screw 70.

115 In this form of locomotive 93 may be provided with a pair of indicating signals or lights as indicated at 74 and 75 which, for example, may be red and green lights, one to indicate the clear position of the track and the other to indicate the danger position or open switch.

120 125 130 In this form of the invention a set of

circuit contact wires are also provided parallelly adjacent the trackway 64, and in the drawings, see Figure 11, these wires are indicated as 76, 77, 78, 79 and 80.

5 The trolley wire is indicated at 81, the motor field is designated at 82 and the motor armature winding is designated at 83. One terminal of the motor field 82 is in electrical communication with the trolley 10 wire 81 through the medium of the wire 84 and the other terminal of the motor field is in electrical communication through the wire 86 with the wire 77 which parallels the trackway. The terminals of the armature winding are in electrical communication with the wires 76 and 78 which parallel the trackway 64 through the medium of the wires 85 and 87 respectively. It will be readily apparent, by reference to Figure 11, 15 that as the switch block, hereinbefore described in detail, is moved to one side or the other from its neutral or switch de-energized position the motor will be energized and caused to operate in a direction in accordance with the side to which the switch block was moved through the various wires just described in like manner as hereinbefore described in detail in connection with the door operating mechanism.

30 For providing for the proper energization of the signals 74 and 75 the operating nut 73 is ground connected, as at 88, to one of the track rails 64. The operating nut 73 is also provided with a contacting finger 89 which is adapted to engage at either of its limits of lateral movement with a pair of contacts 90, each of which cooperates with the respective one of the indicating signals 74—75 above referred to. 35 One of the contacts 90 is joined by a wire 91 with the wire 79 which parallels the trackway and the other of the contacts 90 is joined through the medium of the wire 92 with the remaining wire 80 which parallels the trackway.

40 In this form of the invention the contact making bar 94 is provided with a suitable number of contacting plates to correspond with the number of wires paralleling the trackway, that is, five, and the one of these contacts which is adapted to engage the wire 76 is joined by a wire 96 with one of the contacts 75 of the switch contact mechanism. The one of these plates which 45 is adapted to slidably engage the wire 77 is connected by the wire 97 with the centrally disposed one of the contact blades 75, the one adapted to slidably engage the wire 78 is joined through the medium of the wire 98 with the remaining one of the contact blades 75, the one thereof which is adapted to slidably engage the wire 79 is joined through the medium of the wire 99 with one terminal of the indicating signal 74, and the one thereof

which is adapted to slidably engage the wire 80 is joined through the medium of the wire 100 with one terminal of the indicating signal 75. The remaining terminals of each of the indicating signals 74 70 and 75 are joined together by a cross wire 101, and this cross wire 101 is in turn electrically connected, through the medium of the wire 102, with the wire 97 which connects with the centrally disposed contact 75 and the wire 77 which parallels the trackway 64.

It will be readily apparent, by reference to Figure 11, that when the switch mechanism has been moved to the position indicated in that figure and with the contact block 73 over in position for having its contact fingers engage the contact 90 farthest to the right in that figure, and the contact making arm 94 raised, that a complete electric circuit will be made such as will energize the particular signal 75 through the ground connection and the wire 88, through the block 73, the finger 89, that particular contact 90, its connecting wire 92, the wire 80, the wire 100, through the signal 75, the short portion of the cross overwire 101 between the light 75 and its connection with the wire 102, through the wire 102, the wire 98, the wire 77, the wire 85, through the field 82 of the motor and through the wire 84 to the trolley wire 81. By reference to the said figure it will be observed that when the operating nut 73 is in its opposite position the light 74 will be brought into play in the same manner as above indicated and through its respective wiring circuit.

45 By reason of providing this threaded operating shaft for moving the movable element, either switch or doors, it will be readily apparent that the said element is held locked at either limit of its movement and in fact at any portion of its movement if it should be desired to open the doors partially which, however, is not the case in the preferred operation of the system disclosed.

50 Also by providing the element shifting means with a lost motion feature it will be readily understood that the motor is given a chance to properly pick up speed before the strain of actual operation, incident to the moving of the movable element, is placed upon the motor.

55 While I have illustrated my invention as particularly adapted for operation of mine doors and switches it is evident that the invention may also be used for operating switches of surface railroads and for operating grade crossing gates and the like, and I do not wish to be limited to the particular uses of the invention illustrated but desire it understood that my invention is useful in a variety of ways for operating movable parts from a distance.

From the foregoing description, taken in connection with the accompanying drawings, the complete construction, operation and advantages of my invention will be clear to those skilled in the art to which it appertains.

What I claim is:

1. In mine door and switch operating systems, the combination with the element to be opened or closed, of an electric motor for opening and closing the same, electric circuit controlling means on a mine car for effecting the action of said motor as the car approaches the element to be opened or closed, and signalling instrumentalities including signals on the car and signal operating devices associated with the element to be opened or closed, for indicating to the operator on the car the position of said element.

2. In mine door and switch operating systems, the combination with the element to be opened or closed, of an electric motor for opening and closing the same, connections between said motor and said element to be opened or closed, said connections including means to lock said element in the open or closed position electric circuit controlling means on a mine car for effecting the action of said motor as the car approaches the element to be opened or closed, and signalling instrumentalities including signals on the car and signal operating devices associated with the element to be opened or closed, for indicating to the operator on the car the position of said element.

3. In mine door and switch operating systems, the combination with the element to be opened or closed, of an electric motor for opening and closing the same, electric circuit controlling means on a mine car for effecting the action of said motor as the car approaches the element to be opened or closed, connections between said electric motor and said element including a lost motion device to permit the motor to pick up before moving said element and including means to lock said element in the open or closed position, and signalling instrumentalities including signals on the car and signal operating devices associated with the element to be opened or closed, for indicating the position of said element.

4. In mine door and switch operating systems, the combination with the element to be opened or closed, of an electric motor, power transmission connections including a delayed-action device between said electric motor and the element to be opened or closed whereby said motor will move said part, a trackway through the mine passage, an electrically propelled vehicle movable over the trackway, a trolley wire for supplying electrical energy to the vehicle, a set of fixed circuit contacts paralleling the trackway

and adjacent thereto, means whereby the trolley wire, the motor and the set of circuit contacts are in electrical communication in a broken circuit, and means on the movable vehicle for engaging the set of fixed circuit contacts for completing the circuit to energize the motor, as the vehicle is approaching the position of the element to be opened or closed, a signal on said vehicle for indicating the position of element to be opened or closed and an electrically energized broken circuit adapted to be completed by the circuit completing means and by the movement of the element to be opened or closed for effecting the indicating function of said signal.

5. In mine door and switch operating systems, the combination with the element to be opened or closed, of an electric motor, power transmission connections including a delayed-action device between said electric motor and the element to be opened or closed whereby said motor will move said part, a trackway through the mine passage, an electrically propelled vehicle movable over the trackway, a trolley wire for supplying electrical energy to the vehicle, a set of fixed circuit contacts paralleling the trackway and adjacent thereto, means whereby the trolley wire, the motor and the set of circuit contacts are in electrical communication in a broken circuit, a contact making arm mounted on the movable vehicle and adapted to be lifted into engagement with the set of fixed contacts, a control switch mounted upon said vehicle and adapted for effecting a reversal of the motor, and electrical connections between said switch and said contact making arm.

6. In mine door and switch operating systems, the combination with the element to be opened or closed, of an electric motor, power transmission connections including a delayed-action device between said electric motor and the element to be opened or closed whereby said motor will move said part, a trackway through the mine passage, an electrically propelled vehicle movable over the trackway, a trolley wire for supplying electrical energy to the vehicle, a set of fixed circuit contacts paralleling the trackway and adjacent thereto, means whereby the trolley wire, the motor and the set of circuit contacts are in electrical communication in a broken circuit, a contact making arm mounted on the movable vehicle and adapted to be lifted into engagement with the set of fixed contacts, a control switch mounted upon said vehicle and adapted for effecting a reversal of the motor, and electrical connections between said switch and said contact making arm, a signal on said vehicle for indicating the position of the element to be opened or closed, and an electrically energized broken circuit adapted to be com-

pleted by the switch and circuit completing arm and by the movement of the element to be opened or closed.

7. A mine door and switch operating system comprising the following elements in combination with the element to be opened or closed, an electric motor, power transmission connections including a delayed-action device between said motor and the element to be opened or closed whereby said motor will move said part, a trackway through the mine passage, an electrically propelled vehicle movable over said trackway, a trolley wire for supplying electrical energy to the vehicle, a set of fixed circuit contact wires supported longitudinally of and parallelly adjacent the trackway, an electrical connection between the trolley wire and the motor field, an electrical connection between the said motor field and one of the set of circuit contact wires, an electrical connection between one end of the motor armature winding and one of the set of circuit contact wires, an electrical connection between the other end of the armature winding and one of the set of circuit contact wires, a contact making arm mounted upon the movable vehicle and adapted to be moved into slidable engagement with the set of circuit contact wires, and a control switch means mounted on said movable vehicle for completing and energizing the various circuits formed by the said connections.
8. A mine door and switch operating system comprising the following elements in combination with the element to be opened or closed, an electric motor, power transmission connections between said motor and the element to be opened or closed whereby said motor will move said element, a trackway through the mine passage, an electrically propelled vehicle movable over said trackway, a trolley wire for supplying electrical energy to the vehicle, a set of fixed circuit contact wires supported longitudinally of and parallelly adjacent the trackway, a two-part electric contact adapted to be actuated by said element to be opened or closed during its course of travel, an electrical connection between one part of said two-part contact and ground, an electrical connection between the other part of the two-part contact with one of the set of fixed circuit contact wires, an electrical connection between the trolley wire and the motor field, an electrical connection between the said motor field and one of the set of circuit contact wires, an electrical connection between one end of the motor armature winding and one of the set of circuit contact wires, an electrical connection between the other end of the armature winding and one of the set of circuit contact wires, an indicating signal mounted upon the mov-

able vehicle for indicating the position of the element to be opened or closed, a contact making arm mounted upon the movable vehicle and adapted to be moved into slidable engagement with the set of circuit contact wires, an electrical connection between said signal and said arm, and a control switch means mounted on said movable vehicle for completing and energizing the various circuits formed by the said connections.

9. In a mine door operating system wherein is provided an electric motor and an electric control circuit governed by mechanism on a mine car; the combination with a pair of doors to be opened and closed by said electric motor, of operating screws driven by said motor, means pendent from the doors and cooperative with the operating screws whereby the doors will be caused to move simultaneously toward or from each other by rotation of said screws, said connections including a lost motion device whereby the momentum of said motor may be attained before power is applied from the screws to move the doors.

10. In a mine door operating system, the combination with a pair of doors to be opened and closed, of an electric motor, operating screws driven by said motor, slip clutch connections between said motor and said screws for preventing overloading of said motor, brackets pendent from the doors and cooperative with the operating screws whereby the doors will be caused to move simultaneously toward each other by rotation of said screws, means for providing lost motion in the connection between the bracket and screw connection for the doors, a movable vehicle, a motor circuit control on said vehicle, and means for effecting operative electrical connection between said motor and said vehicle as said vehicle approaches the place where the doors are located, and signaling instrumentalities including signals on the movable vehicle and signal operating devices associated with the doors to be opened and closed, for indicating the position of said doors.

11. In a mine door operating system, the combination with a pair of doors to be opened and closed, of an electric motor, operating screws driven by said motor, slip clutch connections between said motor and said screws for preventing overloading of said motor, brackets pendent from the doors and cooperative with the operating screws whereby the doors will be caused to move simultaneously toward each other by rotation of said screws, means for providing lost motion in the connection between the bracket and screw connection for the doors, a movable vehicle, a motor circuit control on said vehicle, a set of fixed circuit con-

tacts connected with said motor, a movable contact element on said vehicle adapted to be moved into engagement with said fixed circuit contacts as the said movable vehicle passes the same to effect connection between said circuit contacts and said motor to operate the same at the will of the operator,

and signaling instrumentalities including signals on the movable vehicle and signal operating devices associated with the doors 10 to be opened and closed, for indicating the position of said doors.

EDWARD H. GRIM.
